C. MILLER

ELECTRIC FURNACE

Filed Nov. 3, 1922

INVENTOR
Charles Miller
BY
Dunn, Vaughan & Dunn
ATTORNEY

UNITED STATES PATENT OFFICE.

CHARLES MILLER, OF BRIDGEPORT, CONNECTICUT, ASSIGNOR TO MANNING, MAXWELL & MOORE, INC., OF NEW YORK, N. Y., A CORPORATION OF NEW JERSEY.

ELECTRIC FURNACE.

Application filed November 3, 1922. Serial No. 598,793.

To all whom it may concern:

Be it known that I, CHARLES MILLER, a citizen of the United States, residing at Bridgeport, in the county of Fairfield and State of Connecticut, have invented certain new and useful Improvements in Electric Furnaces, of which the following is a full, clear, and exact description, such as will enable others skilled in the art to which it applies to make and use the same.

This invention relates to furnaces and more particularly to improvements in electric furnaces intended for operation at high temperatures.

In furnaces of this type difficulty has been experienced in the commercial use of such furnaces by reason of the fact that at the high temperatures employed, such for example, as in the melting of refractory metals like Monel metal, a great wastage of the walls of the furnace takes place whereby the cost and trouble of maintaining the furnace and of conducting separations therein is great.

An object of this invention is to produce a furnace in which such high temperatures can be quickly and economically attained without serious wastage of the furnace lining.

A further object of this invention is to provide a process by which substances, particularly refractory metals, may be melted economically and effectively and without undue admixture of impurities.

Other advantages will be in part obvious and in part pointed out hereinafter.

The invention accordingly consists in the several steps and the relation and state of one or more of such steps with relation to

each of the others thereof and in the features of construction, combinations of elements and arrangements of parts, both of which will be exemplified in the process and construction hereinafter set forth, the scope and application of which will be indicated in the following claims.

In the accompanying drawing wherein there is shown one of the various possible embodiments of the invention the figure 50 represents a vertical section through the center of a furnace.

As illustrated, the furnace comprises a receptacle 1, and an internal source of heat 2, which source, in order to produce high

temperatures, preferably employs an electric arc.

In order that this source of heat may be concentrated as much as possible upon the material to be heated, it is placed in the interior of the crucible and in such a position as to direct its effect downwardly upon the material to be heated.

The interior of the crucible is preferably of an ovoid form, whereby the walls are positioned along substantially isothermal lines, when the receptacle contains its charge. Such form, moreover, imparts great strength to the receptacle while exposing a minimum surface to the action of the heated gases.

In order, however, to permit and facilitate the insertion of the heating element, along the axis of the crucible, it is desirable that the crucible be truncated whereby an opening is formed at the top, as at 3, which may conveniently be closed by the heating element.

This arrangement shown is provided with electrodes 4 and 5 carried by a suitable support 6 adapted to form a cover for the crucible. It will be understood that the electrodes may be supplied with electric current from any suitable source; if a three-phase source of current is employed it may be convenient to provide three or four electrodes.

Suitable means will be provided for controlling the electric arc. For example, they may be pivoted about the upper ends as at 7, whereby they are caused to swing apart by the magnetic field generated around the electrodes by the current flowing therethrough, but it will be understood that any other suitable means of control may be utilized.

The receptacle is preferably formed from an interior crucible 8, contained within an outer vessel 9, and the space between is filled with a suitable refractory material 10 between them, as for example magnesia, or sand.

This construction prevents air from coming into contact with the outer wall and thus prevents wastage of the crucible, and gives it support.

In order, furthermore, that the material may be conveniently removed from the crucible, a spout is formed as at 11, having a discharge orifice as at 12 above the level of the bottom 13 of the crucible.

The walls of this spout, however, should be attached to the crucible as smoothly as possible, as for example, in the illustration the bottom wall of the spout is made tangent to the interior wall of the crucible as at 14. By this construction there is little or no tendency for the crucible to crack at the juncture of the spout with the body even under the high temperatures to which it is subjected.

It has been found furthermore that the life of the crucible may be materially lengthened and hence the expense of heating the material may be reduced by increasing the thickness of the walls of the upper portions of the receptacle, particularly at or near the opening in the top as at 15. This may be due to the fact that it is in this portion of the furnace that the heated gases from the arc rise and hence it is this portion of the walls which is subjected to the highest temperatures. Furthermore, it has been found that the life of the crucible may be materially lengthened by increasing the thickness of the walls at the juncture of the spout with the body, as shown at 16.

While in general the wastage of the crucible may occur by contact of the hot gases with the interior walls, yet it will also be evident that the crucible itself will attain a high temperature and if its exterior walls were exposed to the air great loss of heat and wastage of the crucible would occur from the exterior of the walls. For these reasons, the form of receptacle with its interior crucible, exterior container, and intermediate insulator, is particularly advantageous.

For different purposes different material may be employed from which to construct the crucible, but it has been found that where high heats are desired as in the melting of Monel metal excellent results may be obtained from the use of a crucible made of graphite.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. In a device of the character described, in combination, a crucible of graphite having an opening in the top thereof, the walls of said crucible being thickened near the top, a cover for said crucible adapted to fit said opening, and a pair of electrodes for an electric arc suspended therefrom.

2. In a device of the character described, in combination, a crucible of graphite having an opening in the top thereof and a discharge spout in the side thereof above the level of the bottom, the walls of said crucible being thickened at the juncture of the spout with the body.

3. In a device of the character described, in combination, a crucible of graphite having an opening in the top thereof and a discharge spout in the side thereof above the level of the bottom, the walls of said crucible being thickened at the juncture of the spout with the body and adjacent the top of the body.

4. In a device of the character described, in combination, a crucible of graphite having an opening in the top thereof and a discharge spout in the side thereof above the level of the bottom, the walls of said crucible being thickened at the juncture of the spout, and adjacent the top thereof, a cover adapted to fit said opening, and a pair of electrodes for an electric arc suspended therefrom.

5. In a device of the character described, in combination, a crucible comprising a body of truncated ovoid form, having a spout upon the side thereof, the lower inner surface of said spout being substantially tangent to and extending upwardly from the lower inner surface of the body, the walls of said crucible being thickened above the level of the bottom of the discharge orifice of said spout.

6. In a device of the character described, in combination, a crucible of graphite comprising a body of truncated ovoid form, having a spout upon the side thereof, the lower inner surface of said spout being substantially tangent to and extending upwardly from the lower inner surface of the body, the walls of said crucible being thickened above the level of the bottom of the discharge orifice of said spout.

In testimony whereof I affix my signature, in the presence of two witnesses.

CHARLES MILLER.
